ATTORNEY

UNITED STATES PATENT OFFICE.

FRANK L. HARRIS, OF STOCKTON, CALIFORNIA

MOTOR-VEHICLE SIGNAL.

Application filed November 9, 1927. Serial No. 232,092.

This invention relates to improvements in signals for motor vehicles of that character which make use of illuminated signs or symbols to indicate an intention on the part of the driver of the vehicle to turn one way or the other or to stop the car.

The principal object of my invention is to combine as a single unit, right-hand, left-hand, and stop signals arranged to be displayed both to the front and rear of the vehicle simultaneously in such manner that this display is had for each sign individually through a single opening in the casing of the signal; and each sign as thus displayed is

15 magnified to an extent considerably greater than the size of the actual sign-symbol itself.

This arrangement therefore causes signals of such size to be displayed as are very readily visible while at the same time the device 20 may be made in a very much smaller and more compact form than would otherwise be possible if the signs themselves were of the magnitude which they apparently are when displayed.

25 These objects I accomplish by means of such structure and relative arrangement of parts as will fully appear by a perusal of the following specification and claim.

In the drawings similar characters of reference indicate corresponding parts in the several views:

Fig. 1 is a sectional central plan of the signal.

Fig. 2 is a longitudinal section taken on the line 2—2 of Fig. 1.

Fig. 3 is a transverse section taken on the line 3—3 of Fig. 1.

Referring now to the numerals of reference on the drawings, the structure comprises a 40 casing 1 having at each end an opening 2 covered by a glass pane 3 which is backed by a screen 4 of fabric or the like which is preferably colored red. The openings 2 are preferably rectangular and are considerably wider 45 than their height. The casing is adapted to be supported from a fixed member of a motor vehicle, such as a fender 5, and so that the casing openings are longitudinally aligned and face to the front and rear of the car, by 50 a bracket 6 or the like.

At its center of length the casing is considerably higher than at its ends, and in the central portion of the casing electric lights 7, 8 and 9 are arranged in vertically spaced relation in a vertical plane midway between the ends of the casing. The central light 8 is

separated from the others by horizontal transverse partitions 10 above and below said light. These partitions at their ends are connected to vertical and transverse opaque 60 panels 11 which project from top to bottom of the casing and are disposed practically half way between the lights and the end openings 2. Each light, therefore, is inclosed in a chamber or compartment separate from 65 the others.

Each panel has a sign symbol cut there-through to individually communicate with the respective light compartments.

The upper symbol is of a nature to indicate a right-hand turn, such as an arrow 12, the central symbol is preferably the word Stop as at 13, and the lower symbol is of a nature to indicate a left-hand turn such as an arrow 14. The lights are so disposed in the 75 various compartments that light rays as at 15 projecting both forwardly and rearwardly from the lights and through the respective sign openings in the panels, cause the shapes of such openings to be thrown on to the 80 screens to a size which will practically cover the entire area of the screens, or about twice as large as the sign openings themselves.

Though I preferably employ a double sign display arrangement, it will be evident that 85 a single sign display device facing in one direction only may also be employed; while maintaining the use of a single window or casing opening for the display of the different signs as well as the enlarged or magnified 90 display of such signs.

The lights are preferably mounted in sockets 16 of ordinary character which are secured into a removable plate 17 mounted on one side of the casing so that the lights may 95 be easily replaced or inspected when necessary.

From the foregoing description it will be readily seen that I have produced such a device as substantially fulfills the objects of the 100 invention, as set forth herein.

While this specification sets forth in detail the present and preferred construction of the device, still in practice such deviations from such detail may be resorted to as do not form 105 a departure from the spirit of the invention, as defined by the appended claim.

Having thus described my invention what I claim as new and useful and desire to secure by Letters Patent is:

110 A signal device including a casing open at one end, a translucent screen across said end,

an opaque panel in the casing behind and spaced from the screen and parallel thereto, said panel having a plurality of vertically spaced signal-symbols cut therethrough, superimposed compartments formed in the casing behind the panel, the symbols registering individually with the different com-

partments, and lights in said compartments disposed relative to the panel and to the screen to cause the outline of all said symbols to be projected in complete and magnified form onto the screen. 10

In testimony whereof I affix my signature.
FRANK L. HARRIS.
